UNITED STATES PATENT OFFICE

JOSEPH M. DEAN, OF SOMERSET, MASSACHUSETTS

LIFE-SAVING EQUIPMENT FOR SUBMARINES

Application filed December 3, 1928. Serial No. 323,470.

The object of my said invention is the provision of a practical and efficient life saving equipment for submarines.

To the attainment of the foregoing the invention consists in the improvement as hereinafter described and definitely claimed.

In the accompanying drawings forming part of this specification:

Figure 1 is a view showing a sunken submarine and also showing what may be properly denominated as the passenger carrier of my improvement as being raised from the submarine through the medium of means on a vessel on the surface, the latter vessel not being illustrated.

Figure 2 is a top plan view showing the said carrier in its normal position in a submarine—i. e. with the upper wall of the carrier flush with the deck of the submarine.

Figure 3 is a horizontal section on an enlarged scale showing the carrier and the casing in which the carrier is normally disposed, and also showing the doors complementary to the carrier and the casing and the arrangement of the said casing relative to compartment walls in the submarine.

Figure 4 is an enlarged transverse section taken in a plane parallel to one end wall of the stationary casing in the submarine and showing a portion of said wall broken away to bring out the fact that both the stationary casing and the carrier are provided with sight glasses.

Figure 5 is a vertical transverse section taken through the stationary casing and the carrier in a plane parallel to that of Figure 4 and showing one of the doors complementary to the carrier.

Similar numerals of reference designate corresponding parts in all the views of the drawings.

In general the submarine 1 may be, and preferably is of the ordinary well known construction or of any other construction compatible with the purposes of my invention.

The interior of the submarine 1 is divided by appropriate walls 2 into compartments, and my improvement is intended to permit sailors to pass from one compartment to another through the improvement, and is also

intended to permit of sailors entering the carrier from different compartments.

The stationary casing of my improvement is designated by 3, and the passenger carrier is designated by 4, the major portions of these elements being preferably of steel, though other material may be employed without affecting my invention.

As will be understood by comparison of Figures 2 to 5, the casing 3 is arranged below the deck 5 of the submarine and is fixed relatively to said deck and the partition walls 2. In opposite walls the stationary casing 3 is provided with openings 6, controlled by doors 7 which are rubber flanged or otherwise appropriately packed, and are equipped with suitable fasteners 8 for detachably securing the doors in closed position when deemed necessary. Fixed guideways 9 are provided at the inner sides of the side walls of the stationary casing 3, and stationary guideways 10 are provided at the inner sides of the end walls of said casing, the guideways 10 being located below and above the before mentioned door openings 6.

The carrier 4 is of hollow form, and is provided with door openings 11 normally in coincidence with the door openings 6 and is also provided with doors 12 rubber flanged or otherwise appropriately packed, and equipped with suitable fasteners 13. Fixed to the sides of the carrier 4 are vertically disposed slides 14 normally arranged in the guideways 9, Figure 3, and fixed to the ends of the carrier 4 are vertically disposed slides 15, located below and above the openings 11 and normally arranged in the guideways 10. The top wall 16 of the carrier 4 extends beyond the side and end walls of said carrier and is normally arranged in a countersink 17 formed in the submarine deck 5 as brought out in Figure 5. Normally, the wall 16 of the carrier 4 is flush with the deck 5 of the submarine, Figure 5, and preferably but not necessarily the extended portion of the wall 16 is detachably connected to the deck 5. The fastening alluded to may be of any appropriate description, though I have shown by way of example headed screws 18 threaded through the extended portion of the wall 16.

16 and into the portion of the deck 5 below the countersink 17. Suitable packing for the exclusion of water designated by 19 is interposed between the extended portion of the wall 16 and the deck portion below said countersink 17, as appears in Figure 5. Manifestly under normal conditions the head of the screws 18 may be countersunk in the upper sides of the wall 16, so as not to offer any projection above said wall 16. A man-hole 20, Figure 2, is provided in the wall 16, said manhole 20 being normally closed by an appropriate door 21 provided when deemed necessary with a handle 22 and with appropriate packing, the latter not being illustrated.

At the points illustrated in Figure 2, the wall 16 is equipped with eyes 23 or other suitable devices, preferably disposed below the upper surface of the wall 16, and designed to be engaged by hooks or the like carried at 24 by branch cables 25 on a hoisting cable 26, the scheme of my invention contemplating the attachment of the cable 26 to the eyes 23 by a diver precedent to the raising of the carrier 4 through the medium of the cable 26 to a vessel on the surface, for the transfer of passengers or sailors from the interior of the sunken submarine to the said vessel on the surface. Through the medium of the walls 27 and 28 a chamber 29 is formed in the carrier 4, and access may be gained to said chamber by a diver on the deck of the submarine through an opening 30 normally controlled by a suitably fastened door 31. Extending through the wall 28 are tubes 32 normally capped at their lower and upper ends as designated by 33 and designed to be connected with means, well known in the art, for supplying the interior of the carrier 4 with air under pressure or oxygen, as occasion demands. Also arranged in the compartment 29 is the threaded end portion of a pipe 34, said pipe 34 being equipped with a cut off valve 33 which is also located in the chamber 29. The pipe 34 extends downwardly from the chamber 29 and terminates adjacent to the bottom wall of the carrier 4 in a branch 36 which communicates at its lower end with the interior of the carrier 4 and is equipped with an upwardly opening nonreturn valve 37. The pipe 34 is also provided with a branch 38 which extends through the bottom walls of the carrier 4 and communicates with the interior of the stationary casing 3 at 39, and is equipped with an upwardly opening nonreturn valve 40. By virtue of the provision just described, a hose (not shown) leading to a pump on the vessel on the surface may be attached to the pipe 34 and the pump alluded to may be utilized to remove water from both the casing 3 and the carrier 4.

As will be understood by comparison of Figures 4 and 5, the casing 3 and the carrier

4 are provided with coincident sight glasses 41 and 42, respectively, whereby persons in the carrier 4 may see into the compartment adjacent to the casing 3 and persons looking from the compartment may observe the interior of the carrier 4 when all of the doors 7 and 12 are closed.

The carrier 4 is preferably, though not necessarily equipped with the ladder 43 and it will also be noted by reference to Figure 5 that the said carrier 4 is provided with a conduit 44 which extends through the bottom of the carrier 4 and is equipped within the carrier with a cut off valve 45.

Normally the equipment constituting my invention is arranged in the submarine with all of the doors 7 and 12 open, and consequently it will be understood that if convenient sailors or passengers in the submarine desiring to pass from one compartment to another may pass through the casing 3 and the carrier 4. It will also be appreciated that when flooding of one compartment adjacent to the casing 3 commences, the casing 3 by the closing of the proper door 7 may be isolated from the said compartment.

The primary purpose of my improvement is to enable sailors in a sunken submarine to be transferred from the interior of the submarine to a rescuing vessel on the surface, and in the use of my improvement it will be understood that when disaster overtakes the submarine, the sailors are to pass from adjacent compartments of the vessel into the stationary casing 3 and the carrier 4, all of the doors 7 and 12 being closed.

When after a disaster to a submarine equipped with my improvement, a rescuing vessel arrives at the place of disaster it is the province of the master of the rescuing vessel to send down a diver equipped with a cable and means for connecting the cable to the eyes or other appropriate devices 23 on the carrier 4. It is the province of the diver when he reaches the deck of the submarine to unfasten the carrier 4 by manipulation of the devices 18 when fastening devices such as 18 are employed, and with this done, and the cable 26 properly attached to the carrier 4, the diver signals the rescuing vessel to take up the cable 26 whereupon the carrier 4 will be raised to the surface after which the passengers in the carrier may be taken therefrom through the manhole 20.

In the above connection it will be understood that in some instances the diver who descends to the sunken submarine may signal by taps for the sailors to enter the carrier 4, and then when the carrier 4 is filled with sailors and all the doors complementary to the improvements are closed, and the occupants of the carrier 4 signal that all is in readiness for the raising of the carrier 4, the diver may signal to the vessel on the surface that the

carrier 4 be raised in the manner before described.

The carrier 4 may be raised and lowered at any time as needed, and in this connection I would have it understood that to facilitate lowering of the carrier 4 the valve 45 is opened to allow water to enter the carrier 4. In the event that no signals are received from the submerged submarine, two divers will be required for the proper operation of my improvement. One diver on the deck of the submarine disconnects the fastenings at 18, whereupon the carrier 4 is raised to the surface, and another diver is then placed inside the carrier 4 with air lines and signal lines. The carrier 4 is then lowered into the position shown in Figure 5, the diver on the deck of the submarine guiding the carrier 4 into engagement with the before mentioned guide ways 9 and 10, and then the diver in the carrier 4 signals to the vessel on the surface to pump the water out of the carrier 4 and also out of the stationary casing 3.

The sight glasses described will enable the diver to observe the conditions in the compartments adjacent to the casing 3.

While I have described but one of my improvements in connection with a submarine, it will be readily appreciated that a submarine may be equipped with any desired number of my improvements, all the improvements being operable in the manner and for the purposes hereinbefore described.

I have entered into a detailed description of the construction and relative arrangement of the elements comprised in the present and preferred embodiment of my invention in order to impart a full, clear and exact understanding of the said embodiment.

I do not desire however, to be understood as limiting myself to the construction disclosed, my invention being defined by my appended claims within the scope of which modifications may be made without departure from my invention.

Having thus described the invention, what I claim as new and desire to secure by Letters Patent is:—

1. In a safety equipment for submarines, a casing fixed in a submarine and open at its upper end and having means for ingress and egress of persons, and a carrier of hollow form removably arranged normally in said casing with its upper end flush with the deck of the submarine and having means for ingress and egress of persons; said carrier being adapted to be lifted from and restored to its position within the casing, means for guiding the carrier out of and into the casing, coincident sight glasses in the casing and carrier, a chamber in the upper portion of the carrier and having an individual door flush with the upper end of the carrier, a conduit having an upper threaded portion and a valve disposed in said chamber and also

having a branch in communication with the lower portion of the carrier and another branch in communication with the interior of the casing, normally closed tube means carried by a wall of said chamber, and a conduit carried by the lower portion of the carrier and communicating with the interior and exterior thereof, and provided within the carrier with a cut off valve.

2. In a safety equipment for submarines, a casing fixed in a submarine and open at its upper end and having means for ingress and egress of persons, and a carrier of hollow form removably arranged normally in said casing with its upper end flush with the deck of the submarine and having means for ingress and egress of persons; said carrier being adapted to be lifted from and restored to its position within the casing, a chamber in the upper portion of the carrier and having an individual top door, and a conduit having an upper open end and a valve disposed in said chamber and also having branches in communication with the interior of the casing and the interior of the carrier, respectively.

3. In a safety equipment for submarines, a casing fixed in a submarine and open at its upper end and having means for ingress and egress of persons, and a carrier of hollow form removably arranged normally in said casing with its upper end flush with the deck of the submarine and having means for ingress and egress of persons; said carrier being adapted to be lifted from and restored to its position within the casing, a chamber in the upper portion of the carrier and having an individual top door and a tube for the supply of fluid to the interior of the carrier, extending through a wall of said chamber and having removable closure devices in the carrier and chamber, respectively.

In testimony whereof I affix my signature
JOSEPH M. DEAN.
